UNITED STATES PATENT OFFICE.

LUDWIG REICHOLD, OF PITTSFIELD, MASSACHUSETTS, ASSIGNOR TO GENERAL ELECTRIC COMPANY, A CORPORATION OF NEW YORK.

RESISTANCE UNIT.

1,394,937.

Specification of Letters Patent. Patented Oct. 25, 1921.

Application filed March 28, 1919. Serial No. 285,743.

To all whom it may concern:

Be it known that I, LUDWIG REICHOLD, a citizen of the United States, residing at Pittsfield, in the county of Berkshire, State 5 of Massachusetts, have invented certain new and useful Improvements in Resistance Units, of which the following is a specification.

My invention relates to electric heating 10 elements of the type in which a resistance conductor is inclosed in a metallic sheath and insulated from it by a thin dense layer of insulating material. Resistance elements of this general type are now in common use 15 in electric heaters and the like and are known as "sheath wire" elements. One of the characteristic features of this resistance element is that the insulating layer between the conductor and the sheath is very thin and 20 very closely compacted so that the conductor is in very intimate thermal relation with the sheath. The usual method of producing such a resistance element is to locate a straight resistance conductor, which may be 25 called the core wire, centrally of a metallic tube which is to form the sheath and fill the tube with an insulating powder, such as magnesia, so as to completely embed and properly center the core wire. The ends of 30 the tube are then plugged, suitable provision being made for the ends of the core wire which extend beyond the tube, and the tube is subjected to a reducing process. The result of this operation is the reduction of 35 both the sheath and the core wire, with the consequent compacting of the insulating material. The arrangement is such that when the core wire is reduced to its desired size, the insulating material is so thoroughly 40 compacted that it becomes practically a unit with the core wire and may be drawn or rolled like a solid metal. Ordinarily the resistance conductor is a straight wire although it has been proposed to employ a 45 spiral wire.

In carrying out my invention I utilize one of the characteristic features of the sheath wire, namely, the compacting of the insulating material by reducing the diameter 50 of the inclosing tube or sheath. The resistance conductor, however, is in the form of a spiral mounted upon a metal support. The conductor is insulated from the support throughout its length but is connected

thereto at one end so that the support carries the current through the tube and both of the terminals are at one end. This is an advantage, especially where a straight heating unit is desired as, for instance, where the unit is to be inserted in an opening in 60 the body or article to be heated.

By this arrangement I may utilize a relatively small wire of considerable length so as to produce a high voltage—low wattage heater, and both of the terminals may be 65 brought out at one end.

In the accompanying drawings illustrating my invention, Figure 1 shows a core or support for the wire; Fig. 2 shows a die for applying insulating material to the core; 70 Fig. 3 shows the core insulated and ready for the wire; Fig. 4 shows the wire wound on the core and ready for insertion in the sheath; Fig. 5 shows the unit ready to be swaged down or reduced; Fig. 6 shows the 75 completed unit; Fig. 7 is a plan view of Fig. 6; and Fig. 8 is a plan view of the die shown in Fig. 2.

Referring to the drawings, 10 represents the metallic core or support for the wire, being provided with a shoulder 11 and flange 12. This core is covered with insulating material throughout its smallest diameter. The particular process which I employ for insulating this core is shown in Fig. 2 and 80 85 consists in inserting the core in a split die 13 having an opening of the same diameter as the shoulder portion 11. A metallic ferrule 14 is inserted in the die near the end of the core and the die is then filled with powdered insulating material which may be magnesium oxid slightly moistened with a thin solution of water and sodium silicate. The material is then compressed on the core by the hollow plunger 15. The die is then 90 95 opened and the core with the insulating material attached thereto removed and allowed to dry so as to harden the insulating material. Fig. 3 shows the core after this operation has been performed. The resistance 100 wire is then wound upon the core, being first wound upon the shoulder portion 11 which is flush with the insulating material and then throughout the insulating material and onto the ferrule 14. The wire may be 105 wound closely with the turns in contact as shown in Fig. 4, since the turns are afterward separated as hereinafter pointed out.

- As shown in Fig. 4 a clamping ring 16 is inserted over the end of the wire so as to insure good electrical contact between the wire and the shoulder portion of the core. 5 Fig. 4 shows the core completely wound and ready for the next operation. The core as shown in Fig. 4 is now introduced into the sheath or tube 17, the end of the tube being closed by a washer 18 insulated from 10 the core. The tube is then filled around the core and wire with a powdered material such as dry magnesium oxid and the upper end of the tube closed by an auxiliary washer 19 which is later removed. The 15 parts are now as shown in Fig. 5. The tube with the parts contained therein now undergoes a reducing process preferably by a swaging or rolling process whereby the diameter is reduced, thereby compressing the 20 material, and lengthening the parts. The insulating material is forced between the turns of the wire and the core 10 reduced in diameter. The material is compacted until there is only a relatively thin layer between 25 the resistance wire and the sheath. The end of the sheath is now cut off so as to remove the washer 19, and a steel washer 20 is inserted over the sleeve 14 in electrical contact therewith. A terminal 21 is secured to the 30 steel washer. A second washer 22 is inserted over the end of the core 10, there being a slot 23 provided for the passage of the terminal 21. This washer 22 is held in place by the riveting over of the core 24 and a 35 terminal 25 is secured to the washer 22. It will thus be seen that I have provided a very rugged and compact form of heating unit which is efficient and conveniently arranged for insertion in bodies or articles to be heated and for other purposes. 40
- While I have described my invention as embodied in concrete form and as operating in a specific manner in accordance with the provisions of the patent statutes, it 45 should be understood that I do not limit my invention thereto as various modifications thereof will suggest themselves to those skilled in the art without departing from the spirit of my invention the scope of which is 50 set forth in the annexed claims.
- What I claim as new and desire to secure by Letters Patent of the United States, is:—
1. The method of making electric heating units which consists in mounting a helical resistance conductor on a support, inclosing the same in a metallic tube, filling the tube with powdered insulating material and then compacting the insulating material by reducing the diameter of the tube. 55
  2. The method of making an electric heating unit which consists in winding a resistance conductor upon a cylindrical core of insulating material, inclosing the same in a metallic sheath, filling the space around the resistance conductor with powdered insulat- 60
- ing material and then compacting the powdered material by reducing the diameter of the sheath. 3. The method of making electric heating units which consists in placing a sinuous resistance element mounted upon a support in a metallic sheath, filling the space around the same with heat refractory insulating material and then compacting the insulating material and forcing it between the turns of the resistance conductor by reducing the diameter of the sheath. 70
4. The method of making electric heating units which consists in placing a sinuous resistance element mounted upon and insulated from a metallic support in a metallic sheath, filling the space around the same with heat refractory insulating material and then reducing the diameter of the sheath and the support to compact the insulating material. 80
5. The method of making electric heating units which consists in placing a sinuous resistance element mounted upon a metallic support and electrically connected therewith at one end in a metallic sheath, filling the space around the same with heat refractory insulating material and then compacting the insulating material and forcing it between the turns of the resistance conductor by reducing the diameter of the sheath. 90
6. The method of making electric heating units which consists in applying powdered heat refractory insulating material to a metallic support, mounting a sinuous resistance element thereon, placing the support in a metallic sheath, filling the space around the same with heat refractory insulating material and then compacting the insulating material and forcing it between the turns of the resistance conductor by reducing the diameter of the sheath. 100
7. The method of making electric heating units which consists in mounting a helical resistance conductor with its turns in contact on a support, inclosing the same in a metallic sheath, filling the space around the same with heat refractory insulating material and then compacting the insulating material and forcing it between the turns of the resistance conductor by reducing the diameter of the sheath. 110
8. The method of making electric heating units which consists in placing a helical conductor with its turns in contact mounted upon and electrically connected at one end with a metallic support in a metallic sheath, filling the space around the same with heat refractory insulating material and then reducing the sheath and the support to compact the insulating material and force it between the turns of the resistance conductor. 120
9. The method of making electric heating units which consists in applying powdered heat refractory insulating material to a metallic support, mounting a helical conductor 125

- with its turns in contact thereon and electrically connecting it therewith at one end, placing said support in a metallic sheath, filling the space around the same with heat 5 refractory insulating material and then compacting the insulating material and forcing it between the turns of the resistance conductor by reducing the sheath.
10. An electric heating unit comprising a metallic sheath, powdered heat refractory insulating material compacted to a hard dense mass within said sheath, a central metallic core therein and a spiral resistance conductor surrounding said core and electrically connected thereto at one end.
11. An electric heating unit comprising a metallic sheath, a central metallic core therein, a helical resistance conductor surrounding said core and powdered heat refractory 20 insulating material compacted to a hard dense mass within said sheath and between the turns of the resistance conductor.
12. An electric heating unit comprising a metallic sheath, a central metallic core therein, insulating material surrounding said core, a helical resistance conductor mounted on said insulation and electrically connected with the core at one end and powdered heat refractory insulating material compacted to a hard dense mass within said sheath and 25 between the turns of the resistance conductor. 30
13. An electric heating unit comprising a metallic sheath, powdered heat refractory insulating material compacted to a hard dense mass within said sheath, a central metallic core therein and a spiral resistance conductor surrounding said core and spaced therefrom by said insulating material but electrically connected thereto at one end. 35 40

In witness whereof, I have hereunto set my hand this 25 day of March, 1919.

LUDWIG REICHOLD.
